UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

VESTIBULE-HOOD.

1,078,306.

Specification of Letters Patent.

Patented Nov. 11, 1913.

Application filed June 28, 1912. Serial No. 706,389.

To all whom it may concern:

Be it known that I, ALLEN E. OSTRANDER, residing at Ridgewood, Bergen county, New Jersey, and being a citizen of the United States, have invented certain new and useful Improvements in Vestibule-Hoods, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an elevation of the end of the vestibule hood, part of the sheathing and supporting means being removed to show the internal construction. Fig. 2 is a plan view looking down on the framework of the hood shown in Fig. 1. Fig. 3 is a longitudinal sectional view taken centrally through the hood on the line 3—3 of Fig. 2, and showing the hood roof sheathing and supporting purlin in position. Figs. 4, 5 and 6 are detailed views of the ramp carline and side plate connection, Fig. 30 being a plan view of the connection uniting a fragment of the side plate with a fragment of the ramp carline. Fig. 5 is an end elevation of the same, looking at the left side of Fig. 4. Fig. 6 is an elevational view looking at Fig. 4 in the direction indicated by the arrow. Fig. 7 is a side elevation of the top of the vestibule end post shown in Fig. 3.

My invention relates to hoods for vestibule cars, and the object of my invention is to provide a form of hood construction reinforced and braced to resist stresses and strains incidental to the use of devices of this character, and adapted to transmit stresses on the same to a substantial part of the car construction.

While the invention will be described in some detail with reference to the hood of the car vestibule, it is, of course, to be understood that the invention is not limited to a vestibule car, but may be used as the overhang hood for passenger and other cars, or may be utilized with obvious mechanical changes and adaptations to any car or similar device.

It is a further object of my invention to provide a hood, the several parts of which are securely and positively united, one to the other, so as to obtain the maximum bracing effect with the minimum amount of material and number of parts.

The invention further consists of novel parts and elements and combination of parts and elements, all as more fully hereinafter described.

My improved hood is shown in position attached to a substantial part of the car-body structure, and this substantial part may be represented by the transversely spaced apart upper side plates 7—7, which plates, as is usual with constructions of this character, are inverted channels and extend the length of the car and beyond the body portion thereof to form a support for the hood, more particularly forming the subject-matter of this invention.

While this hood construction will in all probability be positioned at each end of the car, but one of these hoods will be described in detail, it being understood that this hood construction is duplicated at opposite ends of the car, both hoods being attached to the side plates and deck girders and other material parts of the car roof structure. The side plates extend beyond the body of the car, and are united by means of a casting 8, hereinafter more fully described, to the ends of the upwardly arched ramp carline 9, which ramp carline, as is usual with devices of this character, is an angle-iron supported intermediate its length by the spaced apart vestibule end posts 10, in this instance shown to be in the form of vertically disposed I-beams, the upper end of one flange of which is suitably riveted to the ramp carline on opposite sides of the center thereof. The ramp carline is further supported by means of the corner posts 11, which corner posts in this instance are shown to be in the form of hollow tubes having a rounded outer face, and the upper end of which conforms in configuration to the rounded face 12 of the casting 8, and is suitably affixed to said casting.

Extending transversely of the car and connecting the side plates, preferably at the end of the body portion, is a body end plate 13 having opposite ends riveted to adjacent side plates, and, as shown more particularly in Fig. 3, being of channel shape and having

the web horizontally disposed. This body end plate 13 is supported intermediate its length by the spaced apart door posts 14, in this instance shown to be vertically disposed 5 I-beams resembling the vestibule end posts 10. This structure forms an outline framework for the hood, disposed within which framework is a bracing and reinforcing structure, to which this specification is more 10 especially drawn.

It is to be understood that the shocks in collisions are received on the vestibule end posts and ramp carline, so that in order to withstand the strains of these shocks, and in 15 general to brace the hood to withstand strains incidental to car service, it is necessary to reinforce these posts and carline from the framework of the car-body, and this may be done by bracing the ramp carline and posts from the body end plate and 20 additionally bracing these members from the deck girders. In order to brace the end posts 10 from the body end plate, the end plate 13 is reinforced in a direction to take 25 up these end strains by positioning on the door posts 14, and connecting the side plates 7, a flat forwardly extending anti-telescoping plate 15, forming in effect a truss plate having a broad central portion 16 and narrowing end portions 17. Having their inner 30 ends fastened to the top of the plate 15, preferably at its broad portion 16 through the intermediary of angle-irons 18, are horizontally disposed and longitudinally extending braces 19, the forward ends of 35 which are fastened by means of rivets 51 to the inner face of the web of each of the end posts 10, preferably at some distance below the attachment of the post 10 with the ramp 40 carline 9, as shown more particularly in Figs. 1 and 3. By this construction it will be seen that any shock on the post 10 will be transmitted horizontally and directly to the body end plate 13, and, if desired, additional 45 braces may extend from the posts 10 or ramp carline 9 directly to the body end plate 13, or to its attached reinforcing plate 15. The deck girders 20 also constitute a material part of the car frame and afford additional 50 means for taking up shocks on the car hood. As is usual with car constructions, these deck girders are vertical channel members disposed inwardly from, parallel with, and above the side plates 7. In 55 this instance, the deck girders are shown to terminate in a vertical plane centrally of the end plate 13, and the ends of the deck girders are supported from this end plate by means of a pair of spaced apart transversely 60 disposed substantial right triangular deck girder and body end plate gussets 21. The broad bottom edge of each of said gussets is formed into a bottom flange 22, resting on the web plate 13 and fastened to said web by

means of rivets 23. These gussets each have 65 an outer vertical standing flange 24 engaging the inner face of the deck girder 20 and fastened to the web thereof by means of rivets 25. The deck girders are maintained braced in their spaced apart position by 70 means of the transversely disposed deck girder cross tie 26, which cross tie 26 is in the form of a vertical channel, and has its opposite ends suitably fastened to the upper end of the gusset 21 by means of rivets 27. 75 (See Fig. 1.) By this construction it will be seen that a rigid, heavy, vertically disposed framework is positioned at the end of the car-body, this framework comprising the body end plate 13 carried by the side 80 plates 7 and supported by the door posts 14, the gussets 21 forming the connecting means between the plate 13 and deck girder 20, and the cross tie 26 forming the member extending parallel with and above the end 85 plate 13.

Strains on the post 10 and carline 9 are transmitted directly to the deck girders and to the vertically disposed framework thus described by means of ramp carline braces 90 28, one extending from the outer web of each of the posts 10 to the adjacent end of the deck girder cross tie 26. The ramp carline braces 28 are in the form of outwardly facing vertically disposed channels, having 95 the web portion thereof adjacent the upper end bent at an angle as shown at 31, Fig. 2, to fit flush with and is connected to the web of the deck girder 20 adjacent its upper flange.

The lower outer end of the brace 28 has an angle offset portion 32 integral therewith and extending in a plane at an angle to the plane of the web, so as to fit the outer face of the web of the vestibule end post 10, 105 the reaches 28 being fastened to their respective connecting members by any suitable means, as by riveting. Each of the members 28 is braced on the cross tie 26 by means of top angle gussets 33, a part of one gusset 110 riveted to the upper flange of the cross tie 26, and another part bent to fit the top of the flange of the reach 28, to which it is riveted, as shown more particularly in Fig. 3. A bottom gusset 34 similarly connects 115 the bottom flanges of these members adjacent their meeting point. It will be noted that these braces 28 converge downwardly and forwardly from the deck girders 20 to the posts 10, so that any shock on these posts 120 or attached parts will be transmitted upwardly and outwardly to be taken up by the deck girders. These deck girders are prevented from spreading by means of the cross tie 26, as well as by the car end frame 125 formed by the gussets 21, cross tie 26 and that portion of the body end plate 13 between the gussets.

While forming no particular part of this invention, it is to be understood that the end carline 35, which in this instance is shown to be supported from the deck girder 5 by means of the angles 36, has attached centrally thereof the center hood purlin 37, the lower end of which is suitably riveted to the ramp carline 9 centrally thereof, which purlin has the effect of assisting in transmitting strains from the ramp carline 9 to the carline 35, thus additionally assisting to transmit strains to parts of the car roof structure.

Each end of the side plate 7 is fastened to 15 the adjacent end of the ramp carline 9 by means of a hollow casting 8, hereinbefore referred to, which casting, as shown more particularly in Figs. 4, 5 and 6, comprises a post engaging portion 40, having a curved outer 20 face 12 uniting the front face of the carline with the outside depending flange of the side plates, said rounded face 12 having apertures 46 extending therethrough and affording means for attaching the top of the end 25 posts 11 to the casting, thereby affording a support for the ends of side plates and carline.

Extending from the body portion 40 in directions at right angles to each other is an 30 upwardly extending carline engaging flange 41 and a horizontally extending side plate engaging flange 42, both of the flanges being disposed beneath their respective members and attached to the horizontal webs 35 thereof by means of rivets or other suitable connections. The carline engaging flange 41 is disposed some distance above the flange 42, so as to position the end of the carline above the adjacent end of the side plate, the 40 flanges 41 and 42 being connected by means of the vertically disposed walls 43, extending at an angle to each other, as shown more particularly in Fig. 4. The flange 41 is braced from the adjacent wall 43 by means 45 of an angle bracket 44, formed integral with and disposed in the angle between these members. Similarly the flange 42 is braced from the adjacent wall 43 by means of a pair of transversely spaced apart brackets 50 45, formed integral with the flange 42 and the adjacent side 43 of the body portion 40, and outlining opposite edges of said flange, as shown in dotted lines in Fig. 4. There is also extending downwardly from and integral with the flange 41 a side plate 47 fastened by means of the rivet 48 to the depending front flange of the carline 9, as shown more particularly in Figs. 4 and 6. By this construction it will be seen that the 60 ramp carline and side plates are firmly secured in position to each other and to the end posts by means of a single casting so formed as to bring these members in a correct relative position without the multiplic-

ity of parts characterizing devices of this kind now in general use, and affording additional means for bracing the hood in position on a substantial part of the car structure, and forming a construction in which relative movement between the ramp carline and side plate is eliminated.

As is usual with devices of this character, the framework, hereinbefore described, may be covered by any approved form of metal sheathing or other covering 49 and by the 75 ceiling plates 50, thereby forming a neatly inclosed braced car vestibule hood of improved design.

Having thus described my invention what I claim and desire to secure by Letters Patent is:

1. A platform hood comprising a vertically disposed framework, a horizontally disposed framework connected thereto, and downwardly and forwardly inclined bracing means connecting said vertical and horizontal framework at points remote from their points of connection.

2. A platform hood comprising a vestibule end post, a framework including a horizontally disposed anti-telescoping plate, and a horizontally disposed framework connected thereto, said horizontal framework including a ramp carline connected to said vestibule end post and a horizontally disposed channel connecting said end post with said plate.

3. A car body having side plates, an end plate connecting said side plates, and a truss plate extending beneath fastened to and forming a reinforcement for said end plate, vestibule end posts and means connecting said end posts and said truss plate.

4. A car hood frame including an outlining frame, means bracing said frame, horizontally and vertically inclined means adapted to brace the lower portion of the front edge of said outlining frame to the rear portion of said outlining frame.

5. In the reinforcement of car hoods, including a vestibule end post, a deck girder, a vertical channel cross tie disposed adjacent the top of said deck girder and a downwardly and inwardly inclined brace connecting the end portion of said cross tie with said end post, whereby strains on said post will be transmitted to said cross tie.

6. A reinforcing frame for car hoods comprising a transversely disposed member attached to the deck girders, a pair of converging elements, one end of each element attached to opposite ends of said member, and having the other ends of said elements attached to the vestibule end posts, and gussets connecting said member with said elements.

7. A reinforcing frame for car hoods comprising a transversely disposed member at-

- tached to the deck girders, a pair of converging elements, one end of each element attached to opposite ends of said member, and having the other ends of said elements 5 attached to the vestibule end posts.
8. In a vestibule hood construction, a body end plate, a supplemental plate substantially co-extensive therewith, vestibule end posts, deck girders, and braces connect- 10 ed respectively with said supplemental plate and said deck girders at their inner ends and with said vestibule end posts at their outer ends.
9. In a car construction deck girders, an 15 end plate, a deck girder cross tie of flanged shape connecting the deck girders and spaced flanged plates connecting the deck girders to said end plate.
10. In a car construction, vestibule end 20 posts, deck girders, an end plate and an anti-telescoping plate connected with said end plate, in combination with parallel braces connecting the posts with said anti-telescoping plate and diverging braces connect- 25 ing the posts with said deck girders.
11. In a car construction, a body end plate, an anti-telescoping plate, side plates secured to both of said mentioned plates, vestibule end posts, a flanged brace connect- 30 ing the anti-telescoping plate with said end posts, deck girders relatively above said body end plate and oblique braces connect- ing the deck girders with said vestibule end posts.
- 35 12. In a car construction, deck girders spaced apart, a deck girder cross tie connecting said deck girders, vestibule end posts, a ramp carline connecting said vestibule end posts and diagonally disposed braces con- necting said deck girders and cross tie with 40 said vestibule end posts.
13. In a car construction, side plates, vestibule end posts, a ramp carline lapping and secured directly to said end posts in combination with deck girders, means connecting 45 said girders and diagonal braces lapping the vestibule end posts and deck girders and secured to the end posts and deck girders.
14. In a car construction, a body end plate, an anti-telescoping plate lapping the 50 body end plate, side plates, vestibule end posts, a ramp carline connected with said side plates and end posts, deck girders, and braces connecting said end posts with the side girders and anti-telescoping plate. 55
15. In a car construction, body side plates, a body end plate connecting said side plates, a relatively wide plate lapping the side plates and body end plate, vestibule end posts, a ramp carline connecting the side 60 plates and said end posts and braces lapping said wide plate and end posts and connected thereto.
16. The combination of a side plate, a car- 65 line, a casting connecting said carline with said side plate, said casting having a curved outer face rounding the outer face of the carline into the outer face of the side sill, thereby forming a neat connection between the carline and side plate to accommodate 70 covering sheeting.

In witness whereof I have hereunto set my hand in the presence of two witnesses.

ALLEN E. OSTRANDER.
